US00D611348S

(12) **United States Design Patent**
Handy

(10) **Patent No.:** **US D611,348 S**
(45) **Date of Patent:** **** Mar. 9, 2010**

(54) **BOTTLE**

(75) Inventor: **Francis J. Handy**, Kentland, CA (US)

(73) Assignee: **Method Products, Inc.**, San Francisco, CA (US)

(**) Term: **14 Years**

(21) Appl. No.: **29/333,126**

(22) Filed: **Mar. 3, 2009**

Related U.S. Application Data

(63) Continuation of application No. 29/332,860, filed on Feb. 26, 2009, now Pat. No. Des. 603,708.

(51) **LOC (9) Cl.** **09-01**

(52) **U.S. Cl.** **D9/516**

(58) **Field of Classification Search** D9/682, D9/686, 688, 689, 690, 691, 516, 529, 549, D9/550, 558, 563, 574, 575, 435, 438, 454; 215/379-385; 220/608, 660, 669-675

CLAIM

The ornamental design for a bottle, as shown and described.

DESCRIPTION

FIG. 1 is a perspective view of a bottle showing my new design;

FIG. 2 is a front view thereof;

FIG. 3 is a rear view thereof;

FIG. 4 is a side view thereof, the opposite side view being a mirror image thereof;

FIG. 5 is a top plan view thereof; and,

FIG. 6 is a bottom plan view thereof.

The dashed broken lines in the Figures show environment for illustrative purposes only and form no part of the claimed design. The dot-dashed broken lines in the Figures show an unclaimed border around portions of the subject matter being claimed.

1 Claim, 3 Drawing Sheets
